UNITED STATES PATENT OFFICE

2,469,386

SPUD WRENCH HOLDER

Adolph N. Hanson, Coulee Dam, Wash.

Application January 3, 1947, Serial No. 719,977

4 Claims. (Cl. 224—5)

(Granted under the act of March 3, 1883, as
amended April 30, 1928; 370 O. G. 757)

1

The invention described herein may be manufactured and used by or for the Government of the United States for governmental purposes without the payment to me of any royalty thereon in accordance with the provisions of the act of April 30, 1928 (Ch. 460, 45 Stat. L. 467).

This invention relates to a holder for tools, such as wrenches which are used by riggers, steel workers, linemen and the like, and its object is to retain the tool securely when in any position, and at the same time permit its ready withdrawal from and insertion in the holder.

Many workmen have been injured by tools and wrenches falling on them from fellow workers engaged at higher elevations, and it is an object of this invention to prevent the occurrence of such accidents.

With this in view, the invention consists of a flexible tool holder for attachment to a belt worn by the workman and having certain instrumentalities which securely lock the tool in the holder against accidental displacement when in any position, all of which will be first fully described and afterwards specifically pointed out in the appended claims.

Referring to the accompanying drawing:

Fig. 1 is a front elevation of the tool holder, which in the example shown is designed to hold an end wrench of the type known as a "spud wrench."

Fig. 2 is a side elevation of the same.

Fig. 3 is a front elevation of the holder with wrench in locked position therein, and

Fig. 4 is a side elevation showing the wrench in the holder in full lines and in dotted lines the positions which the wrench, spring locking element and flexible holder assume when the wrench is being withdrawn from the holder.

Like numerals of reference indicate the same parts throughout the several figures, in which:

1 indicates the holder which is preferably of a flexible material such as leather and which is provided with a pair of vertical slots 2 to receive a body belt 3. The holder 1 is also provided with a substantially circular opening 4 in the depending body portion 5 of the holder as shown in the drawing.

Attached to the holder 1, as by rivets 6 about centrally thereof is the stationary leaf 7 of the spring locking element 8. This locking element 8 is similar to a spring hinge, in that it embodies a movable leaf 9 pivotally connected to the stationary leaf 7 by a pintle 10, about which is coiled a spring 11 having one end 12 bearing upon the stationary leaf 7 and its other end 13 bearing

2

upon the movable leaf 9, said spring acting to hold leaves 7 and 9 in substantially the same plane.

It will be noted from Fig. 2 that the movable leaf 9 of the locking element 8 is bent at 14 to form an outwardly and angularly extending neck portion 15 which merges into a cross member 16, which is offset from the flexible holder 1 by the outwardly extending neck portion 15. In elevation 10 the neck portion of the movable leaf 9 and the cross member 16 may be said to be shaped like an inverted T.

17 indicates a spud wrench which has a bifurcated nut engaging end 18 which is offset from 15 the handle 19 by the curved neck or shank 20 which connects the handle 19 with the bifurcated end 18.

Having thus described the several parts of the invention, its operation is as follows:

20 In order to insert the wrench 17 in the holder 1, the movable leaf 9 of the locking element 8 is lifted up out of its normal locking position, and the wrench handle 19 is inserted in the opening 4 of the flexible holder 1 so that the wrench assumes the position shown in full lines in Fig. 4, the bifurcated end 18 of the wrench lying flat against the depending body portion 5 of the flexible holder 1, it being understood that the said opening 4 is large enough to receive the curved 25 offset neck portion 12 of the wrench, but is smaller than the bifurcated wrench head 18, so that said bifurcated head cannot pass through the said opening 4.

When the wrench is in this position, the locking element 8 is permitted to assume its normal 35 position under the influence of the spring 11, so that its outwardly inclined neck 15 assumes a position within the wrench end 18 and between the bifurcated jaws thereof, while the cross member 16 rests upon the face of the bifurcated wrench end, as best shown in Fig. 3. It is therefore seen that the wrench cannot be accidentally displaced from the holder no matter how the holder is turned or positioned so that all danger of the wrench accidentally falling from the holder is eliminated.

50 In order to remove the wrench from its holder, the movable leaf 9 of the locking element 8 is lifted clear of the bifurcated wrench end 18, which permits the wrench to be withdrawn from the flexible holder 1, the depending flexible body portion 5 assuming a position as shown in dotted lines in Fig. 4, thus permitting withdrawal of the 55 wrench in a straight line.

Having thus described the invention, I claim:

1. A spud wrench holder which includes a flexible member having means for connection with a body belt, and provided with an opening for the reception of the handle of a spud wrench and of such size that the bifurcated wrench end will not pass through the said opening, a wrench locking element which includes a stationary leaf permanently attached to the flexible wrench holder adjacent the said opening therein, and which also includes a movable leaf hingedly connected to the stationary leaf and a spring acting upon the stationary leaf and movable leaf to hold the two leaves in substantially the same plane, the said movable leaf including a reduced neck portion adapted to lie within the wrench end and between the bifurcated jaws thereof, and also including a cross member adapted to rest upon the face of the bifurcated wrench end, whereby the wrench is retained against accidental displacement from the holder when the holder and wrench are in any position.

2. A spud wrench holder which comprises a member provided with an opening for the reception of the handle of a bifurcated end wrench, a wrench locking element which includes two hinged leaves, one of said leaves being attached to the said member adjacent the opening therein, the other of which leaves is provided with a reduced neck adapted to lie within the wrench end and between the bifurcated jaws thereof and also provided with a cross member adapted to rest upon the face of the bifurcated wrench end, whereby the wrench is retained against accidental displacement from the holder when the holder and wrench are in any position.

3. A spud wrench holder which comprises a member provided with an opening for the reception of the handle of a bifurcated end wrench, a wrench locking element attached to the said member adjacent the opening therein, a portion of the wrench locking element being adapted to lie within the wrench end and between the bifurcated jaws thereof and having a portion adapted to rest upon the face of the bifurcated wrench end, whereby the wrench is retained against accidental displacement from the holder when the holder and wrench are in any position.

4. A spud wrench holder which comprises a member provided with an opening to receive the handle of a bifurcated wrench, and a wrench locking element attached to the said member adjacent the opening therein and having one portion thereof adapted to lie between the bifurcated jaws of a wrench and another portion thereof adapted to rest against the face of a bifurcated wrench end, whereby the wrench is retained against accidental displacement from the holder when the holder and wrench are in any position.
